FREDERICK DIEHL, OF ELIZABETH, NEW JERSEY, ASSIGNOR TO DIEHL MANUFACTURING COMPANY, A CORPORATION OF NEW JERSEY.

VENTILATING-FAN.

1,099,693.

Specification of Letters Patent.

Patented June 9, 1914.

Application filed June 28, 1909. Serial No. 504,886.

To all whom it may concern:

Be it known that I, FREDERICK DIEHL, a citizen of the United States, residing at Elizabeth, in the county of Union and State of New Jersey, have invented certain new and useful Improvements in Ventilating-Fans, of which the following is a specification, reference being had therein to the accompanying drawings.

10 This invention relates more particularly to an improvement in overhead or ceiling fans and it has for its object to provide means for diffusion of the air current produced by one of such fans through a larger 15 space than the area normally covered by the air current when the axis of movement of the fan blades remains in a fixed position.

The invention consists essentially in mounting the fan-shaft for lateral movement in different planes, and imparting to such fan-shaft, in addition to the propelling movement for generating the air current, lateral movement in different planes by means independent of the force of the said 25 air current.

In its preferred form the fan comprises an electric motor to whose shaft is applied a series of propeller fan-blades, the frame of said motor being pivotally mounted upon 30 a sustaining ring by means of fulcra whose axis passes through the body of the motor, such ring being in turn pivotally mounted upon a supporting frame by means of fulcra angularly arranged in reference to the

35 first mentioned fulcra but whose axis intersects that of the said fulcra. The supporting frame is provided with an annular track or run-way in contact with which rests a traction-wheel in axial relation with the 40 motor-shaft but operatively connected therewith by speed reducing gearing, the rolling of the traction-wheel around said track or run-way imparting to the motor-frame, and thus to the shaft carrying the fan-blades, a 45 continuous gyratory movement upon the angularly arranged fulcra constituting a universal joint connection of the motor-frame with the supporting frame or hanger.

The invention will be understood by reference to the accompanying drawings, in which—

Figure 1 is a perspective view, from above, of an electric ceiling fan embodying the present improvements, Fig. 2 a side elevation of the same with the supporting frame

or hanger and the intermediate ring in partial section. Fig. 3 is a face view of the traction-wheel and its actuating mechanism, with a portion removed to expose the gearing, and Fig. 4 a sectional view of the same. 60 Fig. 5 is a detail sectional view of a portion of the motor frame to show one of the pivotal connections with the rocking ring upon which it is mounted.

The motor is constructed with a frame 65 comprising the yoke 1, and the caps 2 and 3 affording bearing bosses 4 and 5, respectively, for the armature shaft 6 carrying the armature 7 rotating between the field magnet coils 8. The shaft 6, constituting 70 the fan-shaft, has secured thereon a carrier comprising the hub 9 with radiating arms 10 to which are secured the propeller-fan blades 11 rotating within the usual guard in the form of a cage 12 secured to the cap 2. 75

The yoke 1 has arranged at diametrically opposite points in its outer face recesses lined with suitable insulation 13 in which are introduced the ball-cups 14 each provided with an annular ball-race for the anti-friction balls 15 confined therein by means of the centrally apertured washer 16. The rocking ring 17 surrounds the yoke 1 and is provided with diametrically arranged fulcrum-screws 18 having conical points 19 85 projecting inwardly into contact with the anti-friction balls 15 and having their nicked outer ends covered by insulating caps 20.

The outer face of the rocking ring 17 is 90 formed with diametrically arranged recesses upon an axis perpendicular to that of the fulcrum-screws 18, these recesses being lined similarly to those of the yoke 1 with insulating material 21 to receive the 95 ball-cups 22 provided with series of anti-friction balls 23 confined therein by means of the centrally apertured washers 24. The supporting frame or hanger comprises a series of arched radiating arms 25 connected 100 at their upper ends by a circular boss 26 and below the same with a ring 27 having in its upper side the conical track or runway 28. Two of these arms are provided with extensions 29 formed with transverse 105 apertures arranged in alinement and provided with insulating bushings 30 in which are inserted the fulcrum-screws 31 whose tapered inner ends 32 enter the ball-cups 22 through the apertured washers 24 and rest 110

in contact with the anti-friction balls 23, the nicked outer ends of said fulcrum-screws being housed within the insulating buttons 33. It will thus be seen that the angularly arranged pairs of fulcrum-screws 18 and 31, in conjunction with the rocking ring 17, constitute a universal joint connection 10 by means of which the motor-frame is suspended from the supporting frame or base, which in turn is suspended from the hook 34 at the ceiling by means of the tube 35 having its lower end tapped into a socket in the hub 36 and having at its upper end the cap 37 with spaced lugs 38 and transverse bolt 39 engaged by the hook 34.

The bearing boss 5 is shown provided with a bushing 40 fitted upon the shaft 6 and locked in position by means of the screw 41. As represented in the United States patent 20 to F. Diehl and A. F. Becker No. 867,914, dated October 8, 1907, and as shown in Figs. 3 and 4 of the accompanying drawings, the shaft 6 has fixed upon its extremity by means of the set-screw 42 the eccentric 43 encircled by a wearing ring 44 secured within the hub of the gear-wheel 45 by means of the pins 46.

Mounted loosely upon the bearing hub or boss 5 is a sleeve 47 having in its upper face a cavity embracing the eccentric 43. Within the bottom of this cavity is fitted the annular plate 48 having its apertured inner portion fitted to the annular cut-away end portion of the bearing boss 5 and secured to the same by means of fastening screws 49. To the outer periphery of the plate 48 is fitted the correspondingly recessed adjacent face of a ring 50, locked from turning in respect of the same by 40 means of one or more transverse pins 51. This ring 50 is provided with an annular series of gear-teeth to form an internal gear-wheel. The annular plate 48 thus constitutes a rigid connection between the bearing 45 hub 5 and the internal gear-wheel 50 which latter is thus held in fixed relation with the motor-frame.

Overlapping the internally toothed ring 50 is a second internally toothed ring or 50 internal gear 52 having teeth of substantially the same pitch but differing slightly in number from those of the internal gear 50, the gear 52 having a flange extending outwardly beyond the periphery of the gear 50 and being secured by fastening screws 53 to a seat provided therefor in the recessed outer portion of the sleeve 47. The teeth of both internal gears 50 and 52, are engaged upon one side of the armature-shaft by the common intermeshing externally-toothed planet gear-wheel 45 having fitted to its hub the wearing ring 44 mounted upon the eccentric 43, the face of the gear 45 having a width equivalent to the aggregate width of the other two gears.

The gear-cavity within the loose sleeve or housing 47 is closed by a cap-plate 54 fitted upon a seat afforded by the upper extremity of the member 47 and secured thereon by means of fastening screws 55. The 70 cap-plate 54 has a peripheral groove in which is introduced one side of a tire or facing, herein represented as a rubber ring 56 expanded and snapped over the edge of the cap-plate without fastening means other than the sides of the peripheral groove; but it is evident that such facing may be formed of leather or other suitable yielding material in which case it would be retained in position upon the periphery of the cap- 80 plate by suitable fastening means.

The pivotal supports of the motor-frame are preferably disposed upon intersecting axes to form a gimbal-joint and arranged slightly below the center of gravity of the structure, whereby the motor has a tendency to turn over upon its side so as to cause the rim 56 of the traction-wheel afforded by the cap-plate 54 to rest upon the conical track or run-way 28 of the supporting frame or hanger; while the slow rotary movement of the traction-wheel under the action of the differential gearing 45, 50, 52 connecting it with the fan-shaft 6 induces a circular movement of the traction-wheel 54 which produces gyratory differential tilting movements of the motor-frame upon its angularly arranged fulcras 18 and 31 and a resultant motion of the shaft 6 in addition to its normal rotary fan-propelling movement. To insure the requisite rolling contact between the traction-wheel and its track 28, especially when starting the operation of the fan, the screw-pin 57 is tapped centrally through the boss 26, so that its conical point, projecting below the latter, affords a barrier against the retraction of the wheel from the track.

According to the present improvement, the motor-frame 1, and consequently the fan-shaft 6, has a tilting or rocking motion upon two axes in angular arrangement corresponding with the fulcras 18 and 31 both of which are disposed transversely of a fixed line, such as the axis of the suspending tube 115 35, and the tilting means causes the motor-frame to rock upon both of these axes which assume varying angular relation with the fixed axial line in the operation of the fan. By this means, the motor-frame receives its 120 gyratory movements without rotation upon its own axis or that of the fan-shaft. The rocking or tilting movements of the supporting ring 17 and the motor-frame 1 upon their respective axes may be described as 125 rotatory movements, inasmuch as both receive turning movements through a partial rotation. The actuating means from which the motor-body 1 receives turning movements upon its axis or fulcrum 31 is con- 130

trolled or maintained in operation to a certain extent by the turning of the supporting ring or support 17 upon its respective axis 20 which permits the continuous contact of the rim 56 of the traction-wheel with the track or runway 28.

To provide the necessary power for actuating the fan-motor, electric current is led from the generator by means of the cable 58 extending downwardly from the top of the suspending tube 35 through a lateral aperture 59 near the bottom of the same, whence its component conducting wires *a* and *b* are led in opposite directions through apertures 60 in the arms 25 and along the extensions 29 at the lower ends of which they terminate in disks or washers 61 surrounding the fulcrum-screws 31, being clamped upon insulating washers 62 by means of nuts 63 internally threaded to fit the screws 31 and housed within the insulating caps 33. Current is thus conducted from the wires *a* and *b* to the respective ball-cups through the fulcrum-screws 31 and balls 23.

Electrical connection is established between each of the ball-cups 22 and one of the fulcrum-screws 18 by means of a metallic conducting strip 64 lying upon the inner face of the rocking ring 17 and in practice provided with a suitable insulating covering. As represented in Fig. 2, this strip is at one end entered by a screw 65 passing through the bottom of the ball-cup 22 and through a clearance aperture in the recess therefor of the ring 17, the extremity of the conducting strip 64 being clamped upon an insulating washer 66 upon the inner face of the ring 17 by means of the clamp-nut 67. The opposite end of the strip 64 is apertured to embrace the fulcrum-screw 18, and is clamped upon the insulating washer 68 upon the inner face of the ring 17 by means of the clamp-nut 69.

Electrical connection is established between the fulcrum-screws 18 and the motor terminals by means represented in detail in Fig. 5, and substantially as described in relation to the connection shown in Fig. 2. Referring to Fig. 5, the bottom of the ball-cup 14 is provided with an aperture in which is countersunk the head of the screw 70 passing through the aperture of a metallic washer 71 formed upon the end of a conducting wire 72 shown leading to one of the field magnets 8, the screw 70 being insulated from the yoke 1 by passing through a hole of larger diameter extending inwardly through the bottom of the ball-cup socket, and having applied to its threaded extremity the clamp-nut 73 serving to clamp the metallic washers 71 upon the insulating washer 74 upon the inner face of the yoke 1. Current is thus led from the source of supply through the cable 58 and its component wires *a* and *b* to the outer fulcrum-studs 31, and

through the ball-cups 22 and screws 65 through the flat conducting strip 64, whence it passes through the fulcrum-studs 18, ball-cups 14 and screws 70 to wires 72 leading to the motor terminals.

The present improvement is herein shown and described as embodied in an electric ceiling fan of the propeller type in which the entire motor receives a gyratory movement upon the supporting frame by which it is suspended from the ceiling, but it will be readily understood that the improvement is not limited to any specific type of fan or guiding mechanism therefor and that where an individual motor is employed for turning the fan-shaft it is not essential that the motor itself be mounted to tilt in different planes with the shaft or other carrier to which the fan-blades are secured. It is also evident that other means than those shown and described herein may be employed for suspending and imparting the lateral movements to the fan, and that such lateral movements are not necessarily circular, so long as the same are not confined to a single plane, as in a well-known class of desk fans provided with frames to which are imparted oscillatory movements upon fulera disposed in a single axial line.

It will be observed that according to the present construction the fan-shaft not only has, in addition to its rotary movement, a substantially uniform gyratory movement in distinction from those fans in which the motor-frame oscillates, but this gyratory movement is derived from mechanical means including an actuating member fixed upon and thus operatively connected with the fan-shaft, as distinguished from other fans of the same general class in which the oscillatory or rotary movement of the motor-frame is produced by the reaction of the air current induced by the rotation of the fan-blades.

Having thus set forth the nature of the invention, what I claim herein is:—

1. A ventilating fan comprising a motor constructed with a frame, a fan-shaft and a plurality of fan-blades mounted thereon, a support or hanger provided with an endless track, a universal joint connection arranged slightly below the center of gravity of the motor and by means of which the latter is suspended from said support or hanger, a traction-wheel carried by said motor-frame and maintained by gravity in rolling contact with said track, and a driving connection between said traction-wheel and the fan-shaft.

2. A ventilating fan comprising a motor constructed with a frame, a fan-shaft and a plurality of fan-blades mounted thereon, a tilting motor-frame support upon which the motor-frame is pivotally mounted to tilt upon an axis transverse to that upon which said support tilts, and means connected with

said fan-shaft and operating independently of the air current induced by the fan-blades whereby differential tilting movements are imparted to the motor-frame and its support upon their respective axes.

5 3. A ventilating fan comprising a motor constructed with a frame, a fan-shaft and a plurality of fan-blades mounted thereon, a support or hanger provided with an endless track, a universal joint connection by means of which the motor is suspended from said support or hanger, a traction wheel carried by said motor-frame in rolling contact with said track of the support or hanger, and an operative connection between said traction-wheel and the fan-shaft whereby motion is imparted to traction-wheel while the fan is in operation.

10 4. A ventilating fan comprising a motor constructed with a frame, a fan-shaft and a plurality of fan-blades mounted thereon, a support or hanger provided with an endless track, a universal joint connection by means of which the motor is suspended from said support or hanger, a traction-wheel carried by said motor-frame in rolling contact with said track of the support or hanger, an operative connection between said traction-wheel and the fan-shaft whereby motion is imparted to the traction-wheel while the fan is in operation, and means for confining said traction-wheel in contact with said track.

15 5. A ventilating fan comprising a motor constructed with a frame, a fan-shaft and a plurality of fan-blades mounted thereon, a support or hanger provided with an endless track, fulera carried by said support or hanger and arranged in alinement, a rocking ring mounted upon said fulera, fulera carried by said rocking ring in angular arrangement in relation to the first-mentioned fulera and upon which the frame carrying said fan-shaft is mounted to oscillate, a traction-wheel carried by said frame in rolling contact with said track of the support or hanger, and an operative connection between said traction-wheel and the fan-shaft whereby motion is imparted to the traction-wheel while the fan is in operation.

20 6. A ventilating fan comprising a motor constructed with a frame, a fan-shaft and a plurality of fan-blades mounted thereon, a support or hanger provided with an endless track, fulerum-pins carried by said support or hanger and arranged in alinement, a rocking ring, ball-cups mounted in diametrically arranged recesses or sockets in said rocking ring and provided with anti-friction balls engaged by said fulerum-pins, fulerum-pins carried by said rocking ring arranged in alinement with each other and in angular relation to the first-mentioned fulerum-pins, ball-cups mounted in diametrically arranged recesses or sockets in the motor-frame and provided with anti-friction balls engaged by the second-named fulerum-pins, insulating means interposed between the fulerum-pins and the ball-cups and the respective parts by which they are carried, a traction-wheel carried by said motor-frame in rolling contact with said track of the support or hanger, an operative connection between said traction-wheel, and the fan-shaft whereby motion is imparted to the traction-wheel while the fan is in operation.

25 friction balls engaged by the second-named fulerum-pins, a traction-wheel carried by said motor-frame in rolling contact with said track of the support or hanger, and an operative connection between said traction-wheel and the fan-shaft whereby motion is imparted to the traction-wheel while the fan is in operation.

30 7. A ventilating fan comprising a motor constructed with a frame, a fan-shaft and a plurality of fan-blades mounted thereon, a support or hanger provided with an endless track, a universal joint connection by means of which the motor is suspended from said support or hanger, a traction-wheel carried by said motor-frame in rolling contact with said track of the support or hanger, and a speed-reducing driving connection between said fan-shaft and the traction-wheel whereby motion is imparted to the traction-wheel while the fan is in operation.

35 8. A ventilating fan comprising a fan-shaft, a plurality of fan-blades mounted thereon, a frame in which said fan-shaft is journaled, means for driving said fan-shaft, a support or hanger provided with an endless track, fulera carried by said support or hanger and arranged in alinement, a rocking ring mounted upon said fulera, fulera carried by said rocking ring in angular arrangement in relation to the first-mentioned fulera and upon which the frame carrying said fan-shaft is mounted to oscillate, a traction-wheel carried by said frame in rolling contact with said track of the support or hanger, and an operative connection between said traction-wheel and the fan-shaft whereby motion is imparted to the traction-wheel while the fan is in operation.

40 9. A ventilating fan comprising an electric motor constructed with a frame, a shaft and a plurality of fan-blades mounted thereon, a support or hanger provided with an endless track, fulerum-pins carried by said support or hanger and arranged in alinement, a rocking ring, ball-cups mounted in diametrically arranged recesses or sockets in said rocking ring and provided with anti-friction balls engaged by said fulerum-pins, fulerum-pins carried by said rocking ring arranged in alinement with each other and in angular relation to the first-mentioned fulerum-pins, ball-cups mounted in diametrically arranged recesses or sockets in the motor-frame and provided with anti-friction balls engaged by the second-named fulerum-pins, insulating means interposed between the fulerum-pins and the ball-cups and the respective parts by which they are carried, a traction-wheel carried by said motor-frame in rolling contact with said track of the support or hanger, an operative connection between said traction-wheel, and the fan-shaft whereby motion is imparted to the traction-wheel while the fan is in operation.

operation, conducting wires led from the source of supply of electric current to the first-mentioned fulcrum-pins, respectively, electrical connections intermediate each of the first-named ball-cups and one of the second-named fulcrum-pins, and electrical connections intermediate the second-named ball-cups and their respective motor terminals.

10. In a fan, a fan-motor-body having a constant oscillatory movement about an axis fixed with relation to said body and extending at substantially right angles to the plane of said movement, fan blades carried by said body, and means for automatically changing 15 the position of the axis about which said body oscillates.

11. In a fan, a fan-motor-body having a constant oscillatory movement about an axis fixed with relation to said body and extending at substantially right angles to the plane of such movement, fan blades carried by said body, and means for continuously changing the position of the axis about which said body oscillates.

12. A fan comprising in combination a fan-wheel, a motor for driving the same, a carrier to which said motor is pivoted, a support to which said carrier is pivoted, and reducing transmission mechanism driven by 30 said motor arranged to impart motion to the motor about both said axes.

13. In a fan, a base, a support mounted on said base and having rotatory movements relatively thereto, a fan-motor-body having a rotary armature shaft and mounted upon said support to move about an axis extending at an angle to the axis of said support and said shaft, means controlled by the rotatory movement of said support to impart 40 to said fan-motor-body movement about its said axis, and fan-blades carried by said armature shaft.

14. In a fan, the combination with a base, and a support movable about a fixed axis on 45 said base, of a fan-motor-body mounted on said support to move about an axis extending transversely to the first-mentioned axis, and fan-blades carried by said fan-motor-body and rotatable about an axis extending 50 transversely to said axis of said fan-motor-body.

15. A fan comprising a support movable about a fixed axis, a fan-motor-body pivotally mounted on said support on an axis extending at right angles to said fixed axis, fan-blades rotatably mounted on said fan-motor-body, and means controlled by the rotation of said support to oscillate said fan-motor-body about its said axis which extends 60 at an angle to the axis of rotation of said fan-blades.

16. A fan comprising a support rotatable about a fixed axis, a fan-motor-body pivotally mounted on said support on an axis extending 65 at right angles to said fixed axis,

fan-blades rotatably mounted on said fan-motor-body, and means controlled by the rotation of said support to oscillate said fan-motor-body in a plane substantially parallel to the axis of said support and about an axis 70 extending at an angle to the axis of rotation of said fan-blades.

17. In a fan, a base, a supporting frame mounted on said base and having rotatory movement relatively thereto, a fan-motor-body carried by said supporting frame, said supporting frame and fan-motor-body being connected together by bearings sustained by the one and pintles secured to opposite sides of the other and mounted in said bearings 80 whereby said body is free to oscillate about the axis of said pintles, means controlled by the movement of said support to move said fan-motor-body constantly about the axis of said pintles, and fan-blades carried by 85 said body.

18. In a fan, a base, a supporting frame mounted on said base and having rotatory movement relatively thereto, a fan-motor-body carried by said supporting frame, said supporting frame and fan-motor-body being connected together by bearings sustained by the one and pintles secured to opposite sides of the other and mounted in said bearings, a device operatively connected 95 with said body and with said supporting frame to impart constant oscillatory movement to said body about the axis of said pintles, and fan-blades carried by said body.

19. In a fan, a base, a support mounted 100 on said base and having turning movements relative thereto, a fan-motor-body having a rotary armature shaft and mounted on said support to move about an axis extending at an angle to the axis of movement of said support and said shaft, means maintained by the turning movements of said support in position to impart to said fan-motor-body its movements about its axis, and fan-blades carried by said armature shaft.

20. A fan comprising a support pivotally mounted to turn upon a fixed fulcrum, a fan-motor-body pivotally mounted on said support on a fulcrum extending at right angles to said fixed fulcrum, fan-blades rotatably mounted on said fan-motor-body upon an axis at an angle to the fulcrum of the fan-motor-body, and means maintained by the turning movements of said support in position to oscillate said fan-motor-body 115 upon its fulcrum.

21. In a fan, a base, a supporting frame pivotally mounted on said base and having turning movements relatively thereto, a fan-motor-body carried by said supporting frame, said supporting frame and fan-motor-body being connected together by bearings sustained by one and pintles secured to opposite sides of the other and mounted in said bearings whereby said body 125

is free to oscillate about the axis of said pintles, means maintained by the turning movements of said support in position to move said fan-motor-body about the axis of 5 said pintles, and fan-blades carried by said body.

22. In a fan, a base, a supporting frame pivotally mounted on said base and having turning movements relatively thereto, a

10 fan-motor-body carried by said supporting frame, said supporting frame and fan-motor-body being connected together by bearings sustained by one and pintles secured to opposite sides of the other and mounted 15 in said bearings, a device operatively connected with said body and with said base to impart constant oscillatory movement to said body about the axis of said pintles, and fan-blades carried by said body.

20 23. A fan comprising in combination a fan wheel, and supporting and driving means therefor adapted to rotate the same and mounted for motion about a plurality of axes other than the axis of rotation of 25 said fan, and comprising operating means arranged to produce bodily motion of such fan wheel in an endless curvilinear path about such axes, in addition to the rotation of said fan about its own axis.

30 24. A fan comprising in combination a fan wheel, and a motor for supporting and driving said fan mounted for motion about a plurality of axes other than the axis of rotation of said fan and comprising operating means arranged to produce motion of 35 said motor, and with it the fan, about such axes, in an endless curvilinear path.

25. A fan comprising in combination a fan wheel, and driving means therefor mounted for motion about a plurality of 40 axes other than the axis of rotation of said fan, said axes located approximately at right angles to each other, said operating means comprising means arranged to produce bodily motion of said fan about such axes in an 45 endless curvilinear path.

26. A fan comprising in combination a fan wheel, and a motor for driving same mounted for oscillation about a plurality of 50 axes other than the axis of rotation of said fan, said axes arranged approximately at right angles to one another, said motor comprising operating means arranged to produce bodily motion of the motor about both 55 said axes in an endless curvilinear path.

27. In a fan, the combination, with a fan-motor body, and a support therefor, of a bearing comprising two members, one member of said bearing being mounted on and insulated from said fan-motor body and 60 connected to the motor-windings within the same, and the other member of said bearing being mounted on and insulated from said support and connected to an electric circuit, whereby said bearing becomes a part of the 65 fan-motor circuit.

In testimony whereof, I have signed my name to this specification, in the presence of two subscribing witnesses.

FREDERICK DIEHL.
